UNITED STATES PATENT OFFICE.

DAVID MORRIS AND HENRY COFFEE, OF BUNKER HILL, ILLINOIS.

THRASHING-MACHINE.

SPECIFICATION forming part of Letters Patent No. 240,532, dated April 26, 1881.

Application filed December 16, 1880. (No model.)

To all whom it may concern:

Be it known that we, DAVID MORRIS and HENRY COFFEE, both of Bunker Hill, in the county of Macoupin and State of Illinois, have 5 invented a certain new and useful Improvement in Thrashing-Machines, of which the following is a full, clear, and exact description, reference being had to the accompanying drawings, forming part of this specification.

10 Our improvement relates to the construction and operation of reciprocating upright forks, which operate on the straw above the vibrating pan or pans of a thrashing-machine.

Our improvement consists in mounting the 15 forks upon a rotating compound crank-shaft and connecting their upper ends by means of links to the frame of the machine, all of which will be more fully described hereinafter.

In order that our invention may be fully 20 understood, we will proceed to describe it with reference to the accompanying drawings, in which—

Figure 1 is a longitudinal section of a portion 25 of a thrashing-machine having our improvement applied. Fig. 2 is a top view of the same. Fig. 3 is a view through line x x , Fig. 1, looking toward the front of the machine.

A is the case, B the vibrating pan, C the 30 cylinder, D the concave, E the beater, and F the hanging board, of a thrashing-machine, all of which are of common construction, and need no further description in connection with our invention.

35 G is a shaft having suitable bearings in the case of the machine, and constructed with two cranks, H H, projecting in opposite directions. The shaft is furnished with a driving-pulley, I.

40 J J are upright forks mounted, by their arms j j, upon the pins h h of the cranks H H of the shaft G. The forks J preferably have three prongs each, as shown in the drawings, but they may, of course, have more or less.

45 The arms of the forks are divided lengthwise for the reception of links or hangers K K, which are connected in either one of a series of holes, k k, in the upper ends thereof. The links or hangers are hinged to plates or brack-

50 ets L L at the top of the machine case or body A, and are of sufficient length to allow the turning of the shaft.

The object of our device is to loosen up the

straw and cause the separation of any grains of wheat that may be supported in it; and the 55 operation of our device is as follows: The shaft G being rotated, it imparts, in connection with the links, a compound horizontal and vertical reciprocating movement to the forks, as follows: The movement of the forks 60 is first in a downward direction, then backward, then upward, and then forward. Thus as the straw comes upon the vibrating pan from beneath it is caught by the forks in their backward and downward movement and tossed 65 backward and upward by them in their backward and upward movement. By this means the grain is effectually separated from the straw and allowed to pass through the screen at the rear of the pan.

70 It will be observed that the movement imparted to the hooks causes their points to describe a semi-elliptical path, the outer or delivery end being inclined upwardly, as indicated in dotted lines in Fig. 1.

75 The prongs of the forks being curved instead of straight spikes, they will be found more effectual in tossing up and thoroughly loosening the straw, especially when combined, as in the present case, with a vibrating pan or 80 pans.

Having thus described our invention, the following is what we claim as new therein, and desire to secure by Letters Patent:

1. In a thrashing-machine, the combination, 85 with a vibrating pan or pans, of the upright forks J J, constructed with arms j j, compound crank-shaft and pins G H h, and links L L, hinged above and in rear of the said shaft, and to the upper ends of the said arms, and the 90 said arms mounted on the said pins, the whole arranged so as to give a compound horizontal and vertical reciprocating motion to the said forks, the points of the said forks describing a semi-elliptical path, as set forth.

2. The forks J J, having divided arms j j, provided with holes k k, and hinged links K K, in combination with compound crank-shaft G H h, and a vibrating pan or pans, as set forth.

DAVID MORRIS.
HENRY COFFEE.
